DESIGN FOR A FLOWER HOLDER

William W. Goodman, Cincinnati, Ohio

Application May 15, 1941, Serial No. 100,964

Term of patent 3½ years

To all whom it may concern:

Be it known that I, William W. Goodman, a citizen of the United States, residing at Cincinnati, in the county of Hamilton and State of Ohio, have invented a new, original, and ornamental Design for a Flower Holder, of which the following is a specification, reference being had to the accompanying drawing, forming a part thereof.

I claim:

The ornamental design for a flower holder, substantially as shown.

WILLIAM W. GOODMAN.
